UNITED STATES PATENT OFFICE

158,505

SEWER CLEANING MACHINE

Joseph J. Rausch, Berwyn, Ill., assignor to
Howard T. O'Brien, doing business as O'Brien
Manufacturing Co., Chicago, Ill., a corporation
of Illinois

Application November 7, 1947, Serial No. 142,392

Term of patent 7 years

(Cl. D9—2)

To all whom it may concern:

Be it known that I, Joseph J. Rausch, a citizen of the United States, residing at Berwyn, in the county of Cook and State of Illinois, have invented a new, original, and ornamental Design for a Sewer Cleaning Machine, of which the following is a specification, reference being made to the accompanying drawing, forming a part hereof.

In the drawing:

Fig. 1 is a side elevational view of a sewer cleaning machine embodying my new design;

Fig. 2 is a top plan view thereof;

Fig. 3 is an end elevational view as seen from the left hand end in Figs. 1 and 2; and

Fig. 4 is a perspective view of a sewer cleaning machine embodying my new design.

I claim:

The ornamental design for a sewer cleaning machine, substantially as shown.

JOSEPH J. RAUSCH.
